Primary Examiner — Jeffrey D Asch*Assistant Examiner* — Tracey J Bell(74) *Attorney, Agent, or Firm* — Cantor Colburn LLP(57) **CLAIM**

The ornamental design for a mobile phone, as shown and described.

DESCRIPTION

FIG. 1 is a rear perspective view of a mobile phone showing our new design according to a first embodiment;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front perspective view thereof;

FIG. 9 is an enlarged view of the portion 9 encircled in FIG. 1;

FIG. 10 is an enlarged view of the portion 10 encircled in FIG. 4.

FIG. 11 is a rear perspective view of a mobile phone showing our new design according to a second embodiment;

FIG. 12 is a front view thereof;

FIG. 13 is a rear view thereof;

FIG. 14 is a left side view thereof;

FIG. 15 is a right side view thereof;

FIG. 16 is a top view thereof;

FIG. 17 is a bottom view thereof;

FIG. 18 is a front perspective view thereof;

(Continued)

FIG. 19 is an enlarged view of the portion 19 encircled in FIG. 11; and,
 FIG. 20 is an enlarged view of the portion 20 encircled in FIG. 14.

The short dash-dash broken lines illustrating portions of the mobile phone form no part of the claimed design. The dot-dot-dash broken lines enclose portions of the claimed design that are illustrated in enlargements and form no part of the claimed design.
